UNITED STATES PATENT OFFICE.

JAY B. RHODES, OF KALAMAZOO, MICHIGAN, ASSIGNOR TO WESTERN WHEELED SCRAPER COMPANY, OF AURORA, ILLINOIS, A CORPORATION OF ILLINOIS.

DUMP-CAR.

1,168,420.

Specification of Letters Patent. Patented Jan. 18, 1916.

Application filed September 26, 1914. Serial No. 863,612.

To all whom it may concern:

Be it known that I, JAY B. RHODES, a citizen of the United States, residing at Kalamazoo, in the county of Kalamazoo, State of Michigan, have invented certain new and useful Improvements in Dump-Cars, of which the following is a specification, reference being had to the accompanying drawings.

10 This invention relates to dump cars of the type in which the car body or bed is arranged to be tilted at either side to discharge its load, and has particularly to do with dump cars in which the dumping and 15 the righting of the car body are effected through the medium of power supplied from the locomotive.

It is one of the objects of my invention to provide new and improved means for tilting the car body to discharge the load such that by a full stroke of the dumping mechanism the car body can be tilted into position to dump at either side, as desired, and such that by a full stroke of the dumping mechanism the car can be again brought to normal horizontal position.

It is another object of my invention to provide dumping means so arranged that the car body can be tilted to one side and 30 at the same time held against a sharp sudden dumping movement which might have a tendency to jar or shake down a light trestle upon which the car might be located.

It is another object of my invention to 35 provide new and improved means for locking the car body in horizontal position together with automatically-acting means for releasing the car body when the same is to be dumped.

40 It is another object of my invention to provide new and improved means for operating the doors or gates which are ordinarily used in connection with cars of this type.

45 It is another object of my invention to improve devices of this type in sundry details hereinafter pointed out.

The means by which I have accomplished these objects are illustrated in the accompanying drawings and are hereinafter specifically described.

In the drawings:—Figure 1 is a side view

of a car, partly broken away, embodying my improved construction, the supporting wheels of the car being indicated only diagrammatically, the dumping mechanism at the near side of the car having been given a partial operative stroke; Fig. 2 is an end view of my improved car, showing the car body tilted to one side in dumping position, indicating also in dotted lines at one side the normal horizontal position of the car; Fig. 3 is an enlarged detail, partly broken away, being a top view of one of the longitudinally-extending shafts by which the car body locking mechanism is operated; Fig. 4 is an enlarged view, being substantially a central cross-section, showing the dumping mechanism at one side in normal inoperative position and the dumping mechanism at the opposite side in the course of an operative stroke; and Fig. 5 is an enlarged view similar to Fig. 4, but showing the position of the dumping mechanism with the car body tilted into dumping position, showing also at the left the position the operating mechanism assumes for raising the car to normal position.

Referring to the several figures of the drawings in which corresponding parts are indicated by the same reference characters, 10—11 indicate longitudinally-extending I-beams below which are mounted in any suitable manner suitable trucks comprising axles 12 and wheels 13, as shown diagrammatically in Fig. 1. Mounted upon the I-beams 10—11 are standards 14 upon which is pivotally mounted the car bed or car body 15 by means of suitable brackets 16, the pivot pins by which such connection is attained being in alinement whereby the car body can be tipped to one side or the other as may be desired. The I-beams 10—11 have mounted upon their ends suitable coupling devices 17 of any approved type. The car is provided with end walls 18, which are fixed in position upon the bed, and with side gates 19—20 which are mounted as hereinafter described. The bed 15 is provided with buffers 21 at its corners adapted to engage coöperating buffers 22 mounted in any suitable position, upon the framework of the car or upon the trucks.

Upon each end 18 of the car there are

pivotedly mounted two arms 23—24, the two arms 23 extending toward one side of the car having pivotally mounted upon their outer ends the gate 19, and the two arms 24 extending toward the opposite side of the car having pivotally mounted upon their outer ends the gate 20. As best shown in Fig. 2, the pivot pins 25 carried by the gates 19—20 by which pivotal connection is made 10 with the arms 23—24 are placed at one side relative to the central plane of the doors whereby the doors or gates when supported wholly by the arms or bars 23—24 out of contact with the body of the car are adapted 15 to assume substantially the position shown in Fig. 2, stops 26 being provided for limiting the turning of the gates relative to the arms 23—24 whereby the doors are adapted to stand substantially parallel to the position assumed by the body of the car when 20 in dumping position.

Each end 18 of the car is provided at each side with a transversely-extending plate 27 adapted to be engaged by a hook 28 carried 25 by the upper end of a link 29, the lower ends of which links 29 are pivotally connected by means of pins 30 with the ends of brackets or links 31, the other ends of 30 which brackets are pivotally mounted upon the framework by means of trunnions 32. Each of the brackets 31 comprises a plate 33 extending across the edge of the link 29, in the construction shown such plate being formed as an integral part of the bracket. 35 With the brackets 31 at each side of the car in the past-center locking position as shown at the right in Fig. 2, and with the hooks 28 of the four links 29 in engagement with the plates 27 mounted on the car body as shown 40 at the left in Fig. 2, the car body will be held against tilting in either direction, as will be readily understood.

34—35 indicate longitudinally-extending shafts revolvably mounted in the framework 45 above the I-beams 10—11. At each end, each of said shafts has fixed upon it an arm 36, the outer ends of which arms are pivotally connected with the inner ends of links 37, the outer end of each of which links 37 is 50 pivotally connected with one of the brackets 31 by means of a pin 38. In Fig. 2 in the dotted position of the car body the link 37 is omitted so as to avoid unnecessary obscuring of the drawings. As shown in said 55 Fig. 2, the pivotal connection between the arm 36 and the link 37 involves a slot 37^a in the link 37 whereby a slight play is afforded in the action of said parts. As shown at the right in Fig. 2, when the shaft 60 35 is turned to the limit of its motion in clockwise direction in such figure the inner end of the link 37 is brought into engagement with a block 39 carried by the I-beam 11 whereby the link 37 is held against move-

ment inwardly until after the inner end of '65 the link has been raised out of contact with such block 39. It is thus seen that the links 37 serve normally to hold the links 29—31 in their past-center locking position. The I-beam 10 is provided with similar blocks 70 40, one at each end thereof, adapted to engage the upper ends of the links 37 for holding the links 29—31 at that side of the car likewise in their past-center locking position when the arms 36 are in their lower- 75 most position. As will be readily understood, when either one of the shafts 34—35 is turned in a direction to raise the arms 36 carried thereby, the inner end of the link 37 at each end of the car is raised out of 80 contact with the block 40—39 and swung upward and inward, forcing the corresponding bracket 31 inward about the trunnions 32, forcing the links 29 at that side of the car upward so as to permit the car body 85 to be tilted toward the opposite side.

As the car body is tilted toward one side or the other the hooks 28 of the links 29 at the side of the car toward which the car body is tilted are disengaged from the plates 90 27 while the hooks 28 of the links 29 at the opposite side of the car remain in engagement with the plates 27 at that side of the car. As is best shown in Fig. 1, the hook portions of the links 29 stand normally in 95 position underneath the arms 23—24 whereby when the car body is tilted toward one side the arms 23 or 24 at that side of the car are brought into contact with the hooked ends of the links 29. As is best shown in 100 Fig. 2, the upper ends of the links 29 are pivotally connected with the arms 23—24 by means of bars 41—42, whereby the links 29 are held against swinging outward relative to the arms 23—24. As the car body 105 is tilted toward one side the arm 23 or 24 at that side of the car is held against moving downward with the car body whereby the gate 19 or 20 at that side of the car is held in elevated position while the car body 110 moves away from the gate.

Coming now to the means for turning the shafts 34—35 as desired for unlocking the car body for permitting it to be tilted and for turning the car body upon its longitudinally-extending pivot pins, 43—44 indicate channel-bar beams extending transversely of the car at about its middle point and secured in any suitable manner to the longitudinally-extending I-beams 10—11. As shown in 115 Fig. 1 the beams 43—44 are spaced apart, so as to have secured between them two cylinders 45—46 of any suitable type provided with a feed pipe 49 by which air under pressure is adapted to be forced into said cylinders for raising the pistons therein, the air for operating said pistons being supplied 120 from the locomotive or from any other suit- 125

able source. The pistons 47-48 are provided with piston rods 50-51 which are pivotally connected at their lower ends with the pistons. Passing through the piston rods 50-51 in longitudinal direction are two pins 52-53.

54-55 indicate two links pivotally mounted at their lower ends upon the pin 52 and pivotally mounted at their upper ends upon 10 the longitudinally-extending pivot pin 56 by which the bracket 16 at the middle of the car is pivotally connected with the standard 14 carried by the I-beams 10-11 as above described.

15 57-58 indicate links pivotally mounted at their lower ends upon the pin 53 and pivotally mounted at their upper ends upon said pin 56. Upon the links 55-58 there are pivotally mounted latch levers 59-60, the 20 lower ends of which are provided with inwardly-extending hooks 61.

25 Mounted upon the two sections of each of the shafts 34-35 is a sleeve 62, extending outward from which is an arm 63, each of 30 said sleeves being held against rotation relative to its shaft. Revolubly mounted upon the shafts 34-35 adjacent to the arms 63 are two rock-arms 64 provided with longitudinally-extending lugs 65 adapted to engage 35 the under faces of the arms 63. When one of the pistons 47-48 is forced upward by means of compressed air or in any other suitable manner, the pin 52 or 53 corresponding with said piston is moved upward, 40 swinging the arm 55 or 58 upward about the pin 56, moving the latch lever 59-60 upward and carrying upward with it the rock-lever 64 at that side of the car, serving to move upward the arm 63 contacting therewith, and rotating the shaft 34 or 35 in a direction to raise the arms 36 carried by said shaft for moving inward and upward the links 37 at that side of the car for effecting 45 a release of the links 29-31 at that side for permitting the car body to be tilted toward the opposite side. The end of the rock-lever 64 and the hook 61 formed on the end of the latch lever 59-60 are so shaped relative to each other that when the arm 64 has been 50 raised to the desired position for effecting the release of the links 29-31 from locking position, the hook 61 is adapted to automatically slip off from the end of the rock-lever 64, whereupon said lever is adapted to 55 drop the normal position in contact with one of the I-beams 10-11.

56 Mounted upon each of the pins 52-53 is a yoke comprising a cross-bar 65, as best shown in Fig. 1, and two arms 66-67. Upon the lower ends of the arm 66-67 below the pins 52-53 are mounted counterbalance weights 68 which tend to hold the beams normally in the position shown at the right in Fig. 4. The links 55-57 are pro-

vided with blocks 69 adapted to be contacted 65 by the arms 66 to limit the movement of the upper ends of said arms outward. 70 indicates lugs carried by the framework adapted to be engaged by the counterbalance weights 68 when the pistons 47-48 are in their 70 lowermost positions, serving to turn the upper ends of the arms 66-67 inward as shown at the left in Fig. 4. 71 indicates a bearing plate extending across the car at its middle point below the cross-beam 72, 75 said bearing plate being provided at its outer ends with ribs 73 extending longitudinally of the car. The piston rods 50-51 are provided at their upper ends with extensions 74-75, respectively, extending above the 80 pins 52-53 at a slight angle relative to said piston rods.

With the car body in position as shown in Fig. 4, with the operating mechanism at both sides of the car in the condition shown 85 at the left in said figure, and with the means for locking the car body against tilting upon its longitudinally-extending pivots in operative past-center locking position, the car is in condition to receive its load. Whenever 90 it is desired to tilt the car toward one side,—say toward the right in Figs. 4 and 5,—compressed air or other suitable fluid under pressure is admitted to the cylinder 45. The first part of the movement of the piston 47 upward serves to free the counterbalance weight 68 from the stop 70, permitting the upper ends of the arm 66-67 to swing outward under the influence of the counterbalance weights. At the same time upon the 100 upward movement of the piston 47 the shaft 34 is turned in clockwise direction through the medium of the latch-lever 59 and the rock-arm 64, moving the links 29-31 at that side of the car out of their past-center locking position. The cross-bar 65 of the yoke mounted upon the pin 52 very soon is brought into contact with the bearing plate 71 near its outer end whereby said cross-bar is caused to slide outward along the 105 bearing plate into contact with the rib 73. Upon the further movement of the piston 47 the latch-lever 59 is freed from engagement with the rock-arm 64, permitting such rock-arm to fall again to normal position, 110 and the turning movement of the car body through the medium of the arms 66-67 begins.

As above described, upon the continuation 115 of the turning movement of the car body the gate 20 is maintained in its elevated position while the slide of the car is moved out of contact with the gate whereby the material in the car is free to slide sidewise out of the car body. As the car body moves 120 downward at the right in Fig. 5, the under face of the bearing plate 71 comes in contact with the cross-bar 65 of the yoke mount-

- ed upon the pin 53, moving the arms 66—67 of said yoke inward against the action of the counterbalance weights 68 carried by said arms. As the arm 67 of said yoke moves 5 inward a pin 76 extending in a longitudinal direction from said arm is brought into contact with the upper end of the latch-lever 60, releasing said latch-lever from engagement with the outer end of the rock-lever 64.
- 10 When the car is to be righted, the compressed air or other suitable fluid under pressure is admitted to the cylinder 46. As will be readily understood, by reason of the arms 66—67 being held inward by the bearing plate 71, the piston 48 is free to move upward without bringing the arms 66—67 into action to raise the car body. By reason of the latch-lever 60 being held by the pin 76 out of engagement with the rock-lever 64,
- 15 the piston 48 is enabled to be moved upward without a corresponding turning of the shaft 35, whereby the body locking link 29 at that side of the car is maintained in its past-center locking position. Upon the movement of 20 the piston 48 upward, the extension 75 of the piston rod 51 is brought into contact with the bearing plate 71 causing the car body to rise to its normal position. As the car body assumes normal position the hook 28 carried by the link 29 is again brought 25 into engagement with the transversely-extending plate 27 and the gate 20 is again brought into position along that side of the car. As the link 29 on the other side of the car assumes the position shown in dotted lines in Fig. 2 just at the close of the righting operation, the link 29 and the link or bracket 31 are caused to move into their past-center locking position by reason of the 30 weight of the links 37 and the arms 36.
- In case it is desired to dump the contents 35 of the car when in position upon a trestle, or under any other circumstances when it is desired to tilt the car without a jar or jerk, a hook 77 (see Fig. 5) carried by the pin 56 can be thrown about the cross-bar 65 of the elevating yoke at the side of the car toward which the car body is to be tilted, serving to hold the arms 66—67 of said yoke out of 40 operative position. The piston 47—48 at the side of the car toward which dumping is desired can then be elevated to its uppermost position, bringing the extension 74—75 into contact with the bearing plate 71.
- 45 When, thereafter, the piston 47—48 at the opposite side of the car is operated for tilting the car body, the one piston can be permitted to descend as the other piston is brought to its uppermost position, thus letting the car body down gradually and easily to its dumping position. In Fig. 5, I have shown at the left the positions of the parts for dumping in this manner toward the left. With the piston 47 in effective engagement
- 50 with the car-body as shown, the piston 48 65 upon an upward stroke for tilting the car-body toward the left will be prevented from tipping the body abruptly.
- 55 By reason of having a side gate of the car mounted upon a single pivot, the gate 70 is adapted to turn into position parallel with the bottom of the car body when in tilted position so as to afford the greatest possible clearance between the gate and the side of the car body. By reason of the pivotal connection between the links 29 and the arms 23—24, the gate or door 19—20 when in elevated position is free to rise still further relative to the car body in case such a movement is necessary in order to permit 60 the passage of the contents of the car. By reason of the arms 23—24 being mounted at their inner ends at a point above the pivotal connections 25 by which such links are connected with the doors or gates 19—20, the lifting of the arms 23—24 relative to the car-body serves to move the door or gate 65 slightly away from the car body whereby ample clearance is provided.
- 70 In case it is desired to remove the doors 90 19—20 entirely from the car body, this may be accomplished by the withdrawal of the keys 78 by which the arms 23—24 are held in engagement with the pivot pins 25. With the gates 19—20 removed the operation of 95 the car will be just the same as that above described for the car with the gates or doors in position.
- 75 While I have described the operation of the car only as regards dumping in one 100 direction, it will be understood that the operation is precisely similar when the bed is tilted in the opposite direction, the mechanism at one side of the car being the same as that at the other side. I have shown 105 only one hook 77 in the drawings and it will be understood that such hook can be used in connection with either one of the yoke members mounted upon the pins 52—53. If, however, it is found more convenient 110 to provide other means in addition to the hook 77 for holding out of operative engaging position the yoke member at the right hand side of the car as shown in Figs. 4 and 5, suitable means can readily be provided for this purpose without departing 115 from my invention.
- 80 By reason of my improved construction and arrangement of gate-mounting parts, the links 29 are effective for locking the car-bed in normal horizontal position independently of the return of the gate to normal car-closing position. Thus in case a stump or other obstruction prevents the gate from becoming properly seated upon the righting of the bed from tilted dumping position, the bed is locked just the same as if 120 the obstruction were not present.

What I claim as my invention and desire to secure by Letters Patent is,—

1. In a dump car, the combination of a frame, a bed pivotally connected with said frame and adapted to be tilted to discharge its load, two links having hooked engagement at their upper ends with said bed at its opposite sides, means for moving either of said links to permit the bed to be tilted 10 toward the opposite side, and means for locking said links against movement for locking the bed against tilting.

2. In a dump car, the combination of a frame, a bed pivotally connected with said frame and adapted to be tilted to discharge its load, two links having hooked engagement at their upper ends with said bed at its opposite sides, and links each having a pivotal connection at one end with said frame and pivotally connected at its other end with one of said first-named links, said pivotally-connected links at either side of the car being adapted to be moved into a retracted past-center locking position for holding 20 the bed against tilting or into an extended position for permitting the bed to be tilted toward the opposite side.

3. In a dump car, the combination of a frame, a bed pivotally connected with said frame and adapted to be tilted to discharge its load, two links having hooked engagement at their upper ends with said bed at its opposite sides, links each having a pivotal connection at one end with said frame and pivotally connected at its other end with one of said first-named links, said pivotally-connected links at either side of the car being adapted to be moved into a retracted past-center locking position for holding 30 the bed against tilting or into an extended position for permitting the bed to be tilted toward the opposite side, and means for moving said links into and out of their past-center locking positions.

4. In a dump car, the combination of a frame, a bed pivotally connected with said frame and adapted to be tilted to discharge its load, two links having hooked engagement at their upper ends with said bed at 40 its opposite sides, means for moving either of said links to permit the bed to be tilted toward the opposite side, and means for locking said links against movement for locking the bed against tilting, the bed being adapted to be moved downward at either side out of engagement with a hooked link at that side.

5. In a dump car, the combination of a frame, a bed pivotally connected with said frame and adapted to be tilted to discharge its load, two links having hooked engagement at their upper ends with said bed at 50 its opposite sides, means for moving either of said links to permit the bed to be tilted

toward the opposite side, means for locking said links against movement for holding the bed against tilting, and side gates movably mounted relative to said bed, the bed being adapted to be moved downward at either side out of engagement with the 60 hooked link at that side and said link being adapted to limit the downward movement of the gate at that side whereby the bed is adapted to move out of engagement with the gate. 75

6. In a dump car, the combination of a frame, a bed pivotally connected with said frame and adapted to be tilted to discharge its load, two arms pivotally connected at their inner ends with said bed and extending laterally toward one side of the car, a gate mounted upon the outer ends of said arms, and two links having hooked engagement at their upper ends with said bed adapted normally to prevent tilting of the 80 bed toward the opposite side, said hooked links being adapted normally to permit the bed to be tilted toward the side upon which they are located and being adapted to limit the downward movement of said gate 85 whereby when the bed is tilted toward that side the bed moves out of engagement with the gate.

7. In a dump car, the combination of a frame, a bed pivotally connected with said frame and adapted to be tilted to discharge its load, two arms pivotally mounted at their inner ends on said bed upon a centrally-located longitudinally-extending axis, a gate mounted upon the outer ends of said 90 arms adapted to close one side of the car, and two links having hooked engagement at their upper ends with said bed adapted normally to prevent tilting of the bed toward the opposite side, said hooked links 95 being adapted normally to permit the bed to be tilted toward the side upon which they are located and being adapted to limit the downward movement of said gate whereby when the bed is tilted toward that side the bed moves out of engagement with the gate. 100

8. In a dump car, the combination of a frame, a bed pivotally connected with said frame and adapted to be tilted to discharge its load, two arms pivotally mounted at 110 their inner ends on said bed upon a centrally-located longitudinally-extending axis, a gate mounted upon the outer ends of said arms adapted to close one side of the car, two links underlying said arms and 115 having hooked engagement at their upper ends with said bed, and bars pivotally connecting the upper ends of said links with said arms, said links being adapted normally to prevent tilting of the bed toward 120 the opposite side but being adapted normally to permit the bed to be tilted toward the side upon which they are located, and

125

being adapted to limit the downward movement of said gate whereby when the bed is tilted toward that side the bed moves out of engagement with the gate.

- 5 9. In a dump car, the combination of a frame, a bed pivotally connected with said frame, means adapted normally to hold said bed against tilting upon its pivotal axis, means for tilting said bed to discharge its load, arms pivotally connected at their inner ends with said bed, a gate pivotally mounted upon the outer ends of said arms on an axis slightly below the longitudinal central line of the gate and adapted to close 10 one side of the car, said gate when out of engagement with the bed being adapted to turn freely relative to said arms, and means adapted to limit the downward movement of the gate whereby when the bed is tilted toward that side the bed moves out of engagement with the gate.

- 15 10. In a dump car, the combination of a frame, a bed pivotally connected with said frame, means adapted normally to hold said bed against tilting upon its pivotal axis, means for tilting said bed to discharge its load, arms pivotally connected at their inner ends with said bed, a gate pivotally mounted upon the outer ends of said arms and adapted to close one side of the car, said gate when out of engagement with the bed being adapted to turn freely relative to said arms, means adapted to limit the downward movement of the gate whereby 20 when the bed is tilted toward that side the bed moves out of engagement with the gate, and means for limiting the turning of the gate relative to said arms to cause said gate to stand substantially parallel with the bed 25 when the bed is tilted toward that side.

- 30 11. In a dump car, the combination of a frame, a bed pivotally connected with said frame and adapted to be tilted to discharge its load, a reciprocatory member mounted on said frame, means pivotally mounted on said reciprocatory member adapted upon a complete upward stroke of said member to force said bed into dumping position toward the opposite side, and other means 35 rigidly connected with said reciprocatory member adapted upon a complete upward stroke of said member when the bed is tilted toward said member to force said bed into horizontal position.

- 40 12. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in position to engage a bearing on said bed whereby an upward stroke of said reciprocatory member serves to force said bed into dumping 45 position, and means holding said arm

turned against the action of said yielding means whereby when the bed is tilted downward into contact with said arm the arm is moved laterally so as not to engage said bearing upon the succeeding upward stroke 50 of said reciprocatory member.

55 13. In a dump car, the combination of a frame, a bed pivotally connected with said frame and adapted to be tilted to discharge its load, a reciprocatory member mounted on said frame, an arm revolvably mounted on said reciprocatory member, a counterbalance weight carried by said arm tending to hold said arm in position to engage a bearing on said bed whereby an upward stroke 60 of said reciprocatory member serves to force said bed into dumping position, and a stop adapted to hold said arm when in its lowermost position out of operative position whereby when the bed is tilted 65 downward into contact with said arm the arm is moved laterally so as not to engage said bearing upon the succeeding upward stroke of said reciprocatory member.

70 14. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 75 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

80 15. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 85 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

90 16. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 95 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

100 17. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 105 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

110 18. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 115 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

120 19. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 125 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

20. In a dump car, the combination of a frame, a bed pivotally connected with said frame and adapted to be tilted to discharge its load, a reciprocatory member mounted on said frame, an arm revolvably mounted on said reciprocatory member, yielding means tending to hold said arm in operative 130 position to engage a bearing on said bed whereby an upward stroke of said reciprocatory member serves to force said bed into dumping position, and a stop adapted to hold said arm turned out of operative position when in its lowermost position whereby when the bed is tilted downward into contact with said arm the arm is moved laterally so as not to engage said bearing upon the succeeding upward stroke of said reciprocatory member.

- frame, a bed pivotally connected with said frame and adapted to be tilted to discharge its load, means for locking said bed against tilting, a rock-shaft mounted on said frame, means actuated by the turning of said rock-shaft for releasing said locking means for permitting the bed to be tilted, a rock-lever revolubly mounted on said shaft, an arm mounted on said shaft and held against rotation relative thereto; and a lug carried by said rock-lever underlying said arm whereby an upward stroke of said rock-lever serves to rock said shaft.
17. In a dump car, the combination of a frame, a bed pivotally connected with said frame and adapted to be tilted to discharge its load, means for locking said bed against tilting, a rock-shaft mounted on said frame, means actuated by the turning of said rock-shaft for releasing said locking means for permitting the bed to be tilted, a rock-lever adapted by an upward stroke to turn said shaft for releasing said locking means, and means for raising said rock-lever, comprising a latch-lever adapted to engage said rock-lever for raising the same but adapted at a certain predetermined point in the upward stroke thereof to automatically slip out of engagement with said rock-lever.
18. In a dump car, the combination of a frame, a bed pivotally connected with said frame and adapted to be tilted to discharge its load, means for locking said bed against tilting, a rock-shaft mounted on said frame, means actuated by the turning of said rock-shaft for releasing said locking means for permitting the bed to be tilted, a rock-lever adapted by an upward stroke to turn said shaft for releasing said locking means, a reciprocatory member mounted on said frame, means carried by said reciprocatory member adapted upon an upward stroke of said member to tilt said bed into dumping position toward the opposite side, a link pivotally connected at one end with said reciprocatory member and pivotally connected at its other end to said frame, and a latch-lever pivotally mounted on said link adapted to engage said rock-lever for raising it.
19. In a dump car, the combination of a frame, a bed pivotally connected with said frame and adapted to be tilted to discharge its load, means for locking said bed against tilting, a rock-shaft mounted on said frame, means actuated by the turning of said rock-shaft for releasing said locking means for permitting the bed to be tilted, a rock-lever adapted by an upward stroke to turn said shaft for releasing said locking means, a reciprocatory member mounted on said frame, means carried by said reciprocatory member adapted upon an upward stroke of said member to tilt said bed into dumping position toward the opposite side, a link pivotally connected at one end with said reciprocatory member and pivotally connected at its other end to said frame, and a latch-lever pivotally mounted on said link adapted to engage said rock-lever for raising it.
20. In a dump car, the combination of a frame, a bed pivotally connected with said frame and adapted to be tilted to discharge its load, means for locking said bed against tilting, a rock-shaft mounted on said frame, means actuated by the turning of said rock-shaft for releasing said locking means for permitting the bed to be tilted, a rock-lever adapted by an upward stroke to turn said shaft for releasing said locking means, a reciprocatory member mounted on said frame, means carried by said reciprocatory member adapted upon an upward stroke of said member to tilt said bed into dumping position toward the opposite side, a link pivotally connected at one end with said reciprocatory member and pivotally connected at its other end to said frame, and a latch-lever pivotally mounted on said link adapted to engage said rock-lever for raising it, said bed-tilting means carried by said reciprocatory member being adapted to be forced inward by the tilting of the bed toward that side whereby said bed-tilting means is held out of operative position and is prevented from affecting said bed upon the succeeding upward stroke of said reciprocatory member, the forcing inward of said bed-tilting means serving also to release said latch-lever from engagement with said rock-lever.
21. In a dump car, the combination of a frame, a bed pivotally connected with said frame and adapted to be tilted to discharge its load, a reciprocatory member mounted on said frame, means movably mounted upon said reciprocatory member adapted normally upon a complete upward stroke of said member to engage said bed for forcing it into dumping position toward the opposite side, and means for holding said movably-mounted means moved out of operative engaging position.
22. In a dump car, the combination of a frame, a bed pivotally connected with said frame and adapted to be tilted to discharge its load, a reciprocatory member mounted on said frame, an arm pivotally mounted upon said reciprocatory member adapted normally upon a complete upward stroke of said member to engage said bed for forcing it into dumping position toward the opposite side, and means for holding said pivotally-mounted arm turned out of operative engaging position.
23. In a dump car, the combination of a

frame, a bed pivotally connected with said frame and adapted to be tilted to discharge its load, a reciprocatory member mounted on said frame, an arm pivotally mounted upon said reciprocatory member adapted normally upon a complete upward stroke of said member to engage said bed for forcing it into dumping position toward the opposite side, and a hook adapted to be engaged with said 10 arm when the arm is turned inward out of operative position for maintaining said arm out of operative engaging position.

24. In a dump car, the combination of a frame, a bed pivotally connected with said frame and adapted to be tilted to discharge its load, means for locking said bed against tilting, a reciprocatory member mounted on said frame, means movably mounted on said reciprocatory member adapted upon a complete upward stroke of said member to engage said bed for forcing it into dumping position toward the opposite side, said movably-mounted means being adapted to be turned out of operative engaging position 25 by the tilting of the bed toward that side, and other means independent of said movably-mounted means for releasing said bed-locking means.

25. In a dump car, the combination of a frame, a bed pivotally connected with said frame and adapted to be tilted to discharge its load, means for locking said bed against tilting, a reciprocatory member mounted on said frame, means movably mounted on said reciprocatory member adapted upon a complete upward stroke of said member to engage said bed for forcing it into dumping position toward the opposite side, said movably-mounted means being adapted to be turned out of operative engaging position, by the tilting of the bed toward that side, and other means independent of said movably-mounted means for releasing said bed-locking means, said lock-releasing means being adapted to be thrown out of operation when said movably-mounted means is moved out of operative engaging position.

26. In a dump car, the combination of a frame, a bed adapted to be tilted relative to said frame, means for tilting said bed to discharge its load, a gate movably mounted relative to said bed and adapted to close one side of the car, and means for locking said bed against tilting toward the opposite 50 side from that on which said gate is mounted and acting independently of said bed for limiting the downward movement of said gate, said gate being free to move upward relative to said bed and relative to said 55 limiting means.

27. In a dump car, the combination of a frame, a bed adapted to be tilted relative to said frame, means for tilting said bed to discharge its load, a gate movably mounted 60 relative to said bed and adapted to close one

side of the car, and means serving to lock said bed against tilting toward the opposite side from that on which said gate is mounted and acting independently of said bed to limit downward movement of said gate, said 70 gate-limiting and bed-locking means being adapted to lock the bed against tilting whether or not the gate stands in normal car-closing position.

28. In a dump car, the combination of a frame, a bed adapted to be tilted relative to said frame, means for tilting said bed to discharge its load, a gate movably mounted relative to said bed and adapted to close one side of the car, means for locking said 80 bed against tilting toward the opposite side from that on which said gate is mounted, and other means co-operating with said locking means for limiting the downward movement of said gate but adapted to permit free 85 upward movement of the gate.

29. In a dump car, the combination of a frame, a bed adapted to be tilted relative to said frame, means for tilting said bed to discharge its load, two arms one at each end 90 of the car pivotally connected with the bed, a gate mounted on the outer ends of said two arms, links pivotally mounted on said frame and adapted to be brought into engagement with said arms for limiting the downward 95 movement of the gate, and means carried by said links for locking said bed against tilting toward the opposite side.

30. In a dump car, the combination of a frame, a bed adapted to be tilted relative to said frame, means for tilting said bed to discharge its load, two arms one at each end of the car pivotally connected with the bed, a gate mounted on the outer ends of 100 said two arms, links pivotally mounted on 105 said frame and having their upper ends underlying said arms for limiting the downward movement of the gate while at the same time permitting the gate to rise independently, and means carried by said links 110 for locking said bed against tilting toward the opposite side.

31. In a dump car, the combination of a frame, a bed adapted to be tilted relative to said frame, means for tilting said bed to 115 discharge its load, arms pivotally connected at their inner ends with said bed, a gate mounted upon the outer ends of said arms and adapted to close one side of the car, upwardly-extending links mounted on said 120 frame with their upper ends underlying said arms for limiting the downward movement of the gate but permitting the arms to rise out of contact therewith for upward movement of the gate, and means for holding 125 said links against upward movement when the bed is tilted toward that side.

32. In a dump car, the combination of a frame, a bed adapted to be tilted relative to said frame, means for tilting said bed to 130

discharge its load, arms pivotally connected at their inner ends with said bed, a gate mounted upon the outer ends of said arms and adapted to close one side of the car, 5 upwardly-extending links mounted on said frame with their upper ends underlying said arms for limiting the downward movement of the gate but permitting the arms to rise out of contact therewith for upward movement of the gate, means adapted to hold 10

said links against upward movement, and hooks carried by said links adapted to engage the bed for preventing the bed from tilting from normal position toward the opposite side but permitting free downward movement of that side of the bed. 15
